BORING MACHINE

Adolph Storm and Thor Thorsen, Minneapolis, Minn., assignors to Storm Manufacturing Co. Inc., Minneapolis, Minn., a corporation of Minnesota

Application November 7, 1932, Serial No. 641,513

8 Claims. (Cl. 77—2)

Our present invention has for its object to provide a highly efficient portable boring machine for reestablishing, reboring and refinishing bores in an engine cylinder block of accurate size and alignment.

To the above end, generally stated, the invention consists of the novel devices and combinations of devices hereinafter described and defined in the claims.

10 In the accompanying drawings, which illustrate the invention, like characters indicate like parts throughout the several views.

Referring to the drawings:

Fig. 1 is a side elevation of the improved boring machine mounted on an engine cylinder block fragmentarily illustrated in vertical section taken centrally through the bores of said block;

Fig. 2 is a detail view partly in elevation and partly in section taken on the line 2—2 of Fig. 1;

20 Fig. 3 is a view principally in central vertical section taken on the line 3—3 of Fig. 1;

Fig. 4 is a view partly in plan and partly in transverse section taken on the line 4—4 of Fig. 3;

25 Fig. 5 is a view principally in plan with the cover of the upper gear case removed and some parts sectioned on the line 5—5 of Fig. 3;

Fig. 6 is a view partly in elevation and partly in vertical section taken on the line 6—6 of Fig. 5;

30 Fig. 7 is a view partly in plan and partly in transverse section taken on the line 7—7 of Fig. 3;

Figs. 8, 9 and 10 are detail views in section taken on the lines 8—8, 9—9 and 10—10 of Fig. 3, respectively; and

35 Fig. 11 is a perspective view of the cutter removed from the machine.

In the drawings there is fragmentarily illustrated an engine cylinder block 12 on which the improved boring machine is supported in a perpendicular position. A clamp 13 holds the boring machine on the block 12 in axial alignment with one of its cylinders 14.

40 The improved boring machine has an open bottom base 15 and a diametrically extended work passageway 16, the central portion of which is transversely expanded to afford a chamber 17 for a combined cutter and centering head 18 when raised to a position above the bottom of the base 15 or the top of the block 12. The base 15 has an integral upstanding open ended substantially cylindrical housing 19 that is axially aligned with the chamber 17. Formed at substantially the vertical center of the housing 19 is an internal gear chamber 20. Also formed in the housing 19 are two internal bearing seats 21, one of which

is above the gear chamber 20 and the other of which is below the same.

A longitudinally split sleeve bearing 22 is mounted in each seat 21 and which seats and bearings have upwardly tapered engagement, the one with the other, whereby when said bearings are moved upward in the seats 21 they will be contracted to take up wear. Each bearing 22 is adjusted and held where adjusted by a screw collar 23 which engages a shoulder on the housing 19 as a base of resistance. Screws 24 hold the bearings 22 from turning in their seats 21. A long tubular bearing or guide bar 25 for a long tubular boring spindle is mounted in the bearings 22 for compound rotary and endwise feeding movements.

The head 18 is carried by the boring spindle 26 as an extension of its lower end and is detachably secured thereto by a screw stud 27 on said head. Roller bearings 28 are interposed between the head 18 and the guide bar 25 and other roller bearings 29 are interposed between the boring spindle 26 and a ring gear 30, the hub of which is rigidly but detachably secured to the guide bar 25 at its upper end by screw threads, 25 as indicated at 31. These roller bearings 28 and 29 hold the boring spindle 26 in axial alignment with the guide bar 25 for rotation therewith.

The guide bar 25 is rotated at a relatively slow speed with respect to the boring spindle 26, as 30 will presently appear, by an electric motor 32 mounted on a base 33 having a slide 34 held in an upwardly and outwardly inclined way 35 on the housing 19. A set-screw 36 and a slow motion screw 37 adjustably but rigidly secure the slide 34 to the way 35. Obviously, the screws 36 and 37 permit the motor to be raised or lowered to act as a belt tightener.

The driving connections for rotating the guide bar 25 from the motor 32 include a belt 38 which runs over a grooved pulley 39 on the shaft of said motor and a grooved cone pulley 40 on a horizontal shaft 41 journaled in roller bearings 42 mounted in the housing 19. These driving connections further include a worm 43 on the shaft 45 41 in the gear chamber 20 which meshes with a ring worm gear 44 secured to the lower end of a hub 45 on the guide bar 25. This hub 45 is held for rotation with the guide bar 25 by a key 46 which extends into a long keyway 47 in said guide bar and permits the required axial feeding movement of the guide bar. The hub 45 is held against axial movement in the housing 19 by the lower collar 23 and a shoulder on said housing. Access may be had to the interior of the gear 55

chamber 30 through a side opening normally closed by a cover plate 48.

The boring spindle 26 is rotated by the rotary movement of the guide bar 25 but at a relatively fast speed by the following connections which include the gear 30. This gear 30, which is in a gear case 49, meshes with a gear 50 on a shaft 51 journaled in said case. The gear 50 meshes with an idle gear 52 which, in turn, meshes with a gear 53 on a shaft 54 having a large gear 55 which meshes with a gear 56 keyed to the boring spindle 26 above the guide bar 25. The gear case 49 is formed with a cross-head 57 swivelled on the upper end portion of the guide bar 25 but held for common axial movement therewith. The gear 44 rotates the guide bar 25 clockwise and the driving connections 30, 50 to 56, inclusive, drive the boring spindle 26 in the same direction.

The guide bar 25 and the boring spindle 26 which are held for common axial movement are fed endwise to move the head 18 downward by a rack 58 and cooperating pinion 59. This rack 58 is formed on a guide post 60 which extends parallel to the guide bar 25 and is rigidly secured at its lower end to the housing 19. The guide post 60 extends through a sleeve bearing 61 on the cross-head 57 and the pinion 59 is secured to a short shaft 62 journaled in said cross-head and a cover plate 63 for a gear case 64 formed with the cross-head 57.

The pinion 59 is driven from the shaft 51 by the following connections, to wit: Keyed to the shaft 51 is a worm 65 that meshes with a worm gear 66, in a gear case 67 formed with the cross-head 57, secured to a short shaft 68 journaled to the cross-head 57 and a cover plate 69 for the gear case 67.

A gear 70 mounted on the shaft 68 and rigidly secured for rotation with the worm gear 66 meshes with a gear 71 which constitutes the driving member of a cone clutch 72 and has a conical seat 73 for the cone or driven member 74 of said clutch. The gear 71 is rigidly secured to the inner end of a clutch spindle 75 rotatably mounted in a tubular clutch spindle 76 with freedom for a limited relative endwise movement to set or release the clutch 72, as will presently appear. The clutch cone 74 is rigidly secured to the inner end of the tubular spindle 76 which is rotatably mounted in a bearing in the cross-head 57. On the outer end portion of the tubular clutch spindle 76, in the gear case 67, is a pinion 77 which meshes with a gear 78 keyed to the shaft 62 within the gear case 64. The clutch cone 74 and the pinion 77 hold the tubular clutch spindle 76 against endwise movement in its bearing. The spindles 75 and 76 project through an aperture in the cover plate 63 and materially outward thereof and the gear 77 is provided with a long hub which also projects through said aperture and is secured to the tubular spindle 76 by a screw 79 for rotation therewith.

Mounted on the outer end portion of the hub of the gear 77 is a hand wheel 80 secured for rotation therewith by the screws 79. A clutch knob 81 outward of the hand wheel 80 is swivelled to the outer end of the clutch spindle 75 and has screw-threaded engagement with the tubular clutch spindle 76. Obviously by turning the clutch knob 81 on the clutch spindle 76 the connecting screw threads will move the clutch spindle 75 endwise in the tubular spindle 76 and axially shift the gear 71 which contains the clutch seat 73 to set or release the clutch 72. Obviously when the clutch 72 is set the rotation of the pinion 79 on the rack 58 will move the cross-head 57

downward on the guide post 60 and thereby feed the boring spindle 26 to its work. When the clutch 72 is released the hand wheel 80 may be manipulated to rotate the pinion 59 and thereby raise or lower the boring spindle 26.

A novel device in the form of a drag ring 82 is provided to prevent the guide bar 25 and parts carried thereby from moving downwardly in the housing 18 under the action of the weight thereof and thereby produce an unsteady feed to said bar. This drag ring 82, which encircles the guide bar 25 in the gear chamber 20, is transversely divided and the ends thereof spaced to receive the key 46 therebetween with sufficient clearance to permit the required contraction or expansion of said ring. Primarily, the internal diameter of the drag ring 82 is slightly smaller than the external diameter of the guide bar 25 so that the same is slightly expanded when applied thereto to frictionally connect the same. The external surface of the drag ring 82 is downwardly and inwardly tapered and mounted in a correspondingly formed seat 83 in the upper end portion of the hub 45 with freedom for slight axial movement in said seat. Obviously, the weight of the guide bar 25 and parts carried thereby on the drag ring 82 tends to move said ring downward. Independent downward movement of the guide bar 25 ahead of its feeding mechanism, due to lost motion in the feed gearing, is thus prevented, as the normal friction between the engaging surfaces of the drag ring 82 and bar causes the ring to move downward with the bar in its tapered seat 83 and thereby further contract the same and increase the frictional engagement between the drag ring 82 and the guide bar 25.

During the lifting or retracting movement of the guide bar 25 the drag ring 82 will be moved thereby upward from its tapered seat 83 and permit the hinge to expand thus reducing the frictional contact between the drag ring 82 and guide bar 25 to facilitate said movement of the guide bar 25.

A cutting tool 84 is carried by a holder 85 removably mounted in a radial seat 86 in the head 18 near the underside thereof. This holder 85 may be adjusted radially in the seat 86 by a screw-acting member 87 to set the cutting tool 84 the proper distance from the axis of the head 18 to cut the walls of the respective cylinder to the desired diameter. The adjusting member 87 has threaded engagement with the holder 85, projects rearward therefrom and impinges against the head 18 at the rear end of the seat 86 as a base of resistance.

A centering device is provided for centering the machine with respect to one of the cylinders 14 to be re bored or refinished previous to securing said machine to the block 12 by the clamp 13. This centering device includes three radial fingers 88 mounted in seats in the head 18 above the holder 85 and spaced equi-distances apart circumferentially about said head. These fingers 88 are simultaneously projected for engagement at their outer ends with the walls of the cylinder 14 or retracted by a rotatable disc 89 mounted in the head 18 and having on its under side a spiral screw thread 90 which meshes with racks 91 on the fingers 88.

The disc 89 may be manually rotated from the top of the machine by the following connections, to wit: A long operating rod 92 extending axially through the tubular boring bar 26 and head 18 has on its lower end a gear 93 that is connected by an idle gear 94 to an internal ring gear 95

rigidly secured to the disc 89. On the upper end of the rod 92 is an operating knob 96 having a hub 97 turnably mounted on the upper end portion of the boring bar 25 and in a bearing 98 on the cover plate 99 for the gear case 49. Obviously by turning the operating knob 96 the centering fingers 88 may be projected or retracted, at will.

The clamp 13, as shown, is in the form of a horizontal bar having at one end a fork, the prongs of which straddle the housing 19 and rest on the base 15 at diametrically opposite points. In the under side of the body of the clamp 13 is a longitudinally extended T-slot in which the head 15 of an anchor bolt 100 is slidably mounted at the front end thereof. This anchor bolt 100 extends loosely through a transverse bar 101 which rests on the top of the block 12 over the cylinder 14 adjacent to the one to be bored and has threaded engagement with a nut 102 which connects the prongs of a U-shaped strap 103 having at its lower end a transverse channel anchor bar 104 that is intermediately pivoted thereto. This anchor bar 104 engages the blocks 12 at its under side at diametrically opposite sides of the cylinder 14 through which the anchor bolt 100 extends. A coiled spring 105 is compressed between the body of the clamp 13 and the bar 101.

The body of the clamp 13, at its rear end, is held raised by a hand screw 106 to press its prongs onto the base 15 and thereby frictionally hold the machine on the top of the block 12. This hand screw 106 extends through a large hole in the body of the clamp 13, has screw-threaded engagement with a nut 107 slidably mounted in the slot of said body. On the lower end of the hand screw 106 is a foot 108 connected thereto by a universal joint and which foot rests on the block 12.

In the motor circuit is a cut-out switch 109 and a vertically adjustable collar 110 on the guide bar 25 is provided for opening said switch at the limit of the downward feed of the guide bar 25.

Operation

The operation of the improved boring machine may be briefly described as follows: The driving connection from the motor 32 to the guide bar 25 rotates said bar at a relatively slow speed and the train of gears from the guide bar 25 to the boring spindle 26 rotates said spindle at a relatively fast speed. The object of the differential speed at which the guide bar 25 and the boring spindle 26 are rotated is to increase the accuracy of the machine by causing the cutting tool to move about a given center and not drift. In other words, the tool spindle bearing being constantly rotated as a whole about a common center with reference to the object being bored causes any inaccuracies in the boring construction, such as would permit the tool to drift or be offcenter, to move about a circular path and thus evenly distribute the inaccuracies of the bearing around the entire circumference of the cylinder being bored. It is well known that if a drill or other boring tool is not held in a true position at the beginning of the bore, it will drift from a given center, with the result that the bore is not in true alignment. By rotating the guide bar 25 or bearing in which the boring spindle 26 is rotatably mounted and at a different speed, any inaccuracy which would tend to cause the cutting tool to drift is constantly shifted about a given center and hence the cut is made at said center and on a true axial line.

The guide bar 25 is moved axially by rack 58

and co-operating pinion 59 and which pinion is driven by connections actuated by the rotary movement of said bar to feed the same downwardly.

The object of the retarding device or drag ring 82 for the guide bar 25 or bearing for the boring spindle 26 is to overcome the uneven feed of said bearing and hence that of the boring spindle 26 by the rack 58 and pinion 59. This uneven feed is caused by play between the teeth of the rack 58 and pinion 59. Obviously, as the teeth of the pinion 59 move out of engagement with the teeth of the rack 58, during the downwardly feeding movement of the guide bar 25, the weight of said bar and parts carried thereby would cause a slight intermittent gravity feed of the bar independent and ahead of the gear feed with a resultant unsteady feed imparted to the cutting tool.

The drag ring 82, by its breaking frictional engagement with the guide bar 25 on downward movement of the bar, prevents any gravity feed of said bar so that the guide bar 25 is positively moved downward by the rack 58 and pinion 59 with a steady and even feed. As previously stated, the frictional contact between the drag ring 82 and the guide bar 25 is automatically increased during the downward movement of the guide bar 25 and automatically released by the upward movement of the guide bar 25.

While the driving connections illustrated in the drawings are designed to rotate the guide bar 25 and the boring spindle 26 in the same direction, it will, of course, be understood that connections may be designed to rotate said bar and spindle in reverse directions with the same result.

What we claim is:

1. In a machine of the class described, a base, a bearing rotatably mounted on the base, an upright boring spindle rotatably mounted in the bearing, means for rotating the bearing, feeding means for moving the bearing downwardly, a contractile and expansible drag ring through which the bearing extends axially, said ring being frictionally clamped onto the bearing, and a member held against axial movement with respect to the bearing and having a tapered seat for the drag ring, the taper of the seat being arranged to contract the drag ring during the feeding movement of the bearing.

2. In a machine of the class described, a base, a bearing mounted on the base for compound rotary and axial movement, an upright boring spindle rotatably mounted in the bearing, means for rotating the bearing, a feed device for moving the bearing axially, a sleeve keyed to the bearing for rotation therewith but held against relative axial movement, said sleeve having an internal annular seat that is downwardly and inwardly tapered, and a transversely divided drag ring in the seat and frictionally clamped onto the bearing and positively held for rotation therewith.

3. In a machine of the class described, a base, a tubular bearing carrying member mounted for rotatable and axial sliding movement through the base, a tubular boring spindle rotatably mounted in and coaxially supported by the bearings of said tubular bearing carrying member, a cutting tool carried solely by the boring spindle for rotation therewith, means extending coaxially through the boring spindle and operatively connected to the cutting tool for adjusting the same radially from the upper end of said boring spindle, and means for constantly rotating the tubular bearing carrying member and boring

spindle at relatively low and high speeds respectively during normal operation of the machine.

4. In a machine of the class described, a base 5 a tubular bearing mounted for rotatable and axial sliding movement through the base, a boring spindle concentrically mounted in and supported by said bearing, a cutting tool fixed to the lower end of said spindle for rotation therewith, means for rotating the bearing, and means 10 operated by the rotary movement of the bearing for constantly rotating the boring spindle at a different speed from that of the bearing.
5. In a machine of the class described, a base, 15 a tubular bearing carrying member mounted for rotatable and axial sliding movement through the base, a boring spindle concentrically mounted in and supported by the bearings of said tubular member, a cutting tool carried solely by the boring spindle for rotation therewith, means for 20 rotating said tubular bearing carrying member, and a train of gears for rotating the boring spindle from the tubular member at relatively higher speed.
- 25 6. In a machine of the class described, a base, a tubular bearing carrying member mounted for rotatable and axial sliding movement through the base, a tubular boring spindle rotatably mounted in and supported by the bearing of said 30 tubular bearing carrying member, a combined cutting and centering head secured to one end of said tubular boring spindle for rotation therewith, movable centering members mounted in said head, means rotatable with the boring 35 spindle for adjusting said centering members from the other end of said tubular boring spindle, comprising an operating rod extending axially through the boring spindle and boring

means at its inner end operatively engaging the centering members, and hand operated means mounted on the outer end of said spindle and operatively connected to the outer end of said rod.

- 5 7. In a machine of the class described, a base, an upright boring bar mounted on the base for compound rotary and axial movements, a feed device for moving the bar axially, a rotatable member surrounding said bar and held against axial movement in the base, said member having a tapered annular seat at its upper end, adjacent said bar, and a retarding device for holding the bar against downward movement independently and ahead of said feed device, said retarding device comprising a contractible and expansible friction ring surrounding the bar for rotation therewith and having a tapered face adapted to cooperate with the tapered seat in said rotatable member.

- 10 8. In a machine of the class described, a base, a guide post upstanding from said base, a tubular bearing carrying member mounted for rotatable and axial sliding movement through the base parallel to said guide post, a boring spindle concentrically mounted in and supported by the bearings of said tubular member, a cutting tool mounted on the lower end of said boring spindle for rotation therewith, a gear casing mounted on the upper end of said tubular member and slidably mounted on said guide post, and gearing journaled in said casing and operatively connecting said tubular member and boring spindle for relatively different speeds of rotation.
